UNITED STATES PATENT OFFICE.

EDGAR H. FREEMAN, OF TRENTON, NEW JERSEY, ASSIGNOR TO E. H. FREEMAN ELECTRIC COMPANY, OF TRENTON, NEW JERSEY, A CORPORATION OF NEW JERSEY.

PORCELAIN PULL-SOCKET.

1,262,320.

Specification of Letters Patent.

Patented Apr. 9, 1918.

Application filed November 8, 1915. Serial No. 60,400.

To all whom it may concern:

Be it known that I, EDGAR H. FREEMAN, citizen of the United States, residing at Trenton, in the county of Mercer and State 5 of New Jersey, have invented certain new and useful Improvements in Porcelain Pull-Sockets, of which the following is a specification.

This invention relates to electrical pull 10 sockets of the type wherein a pull chain, cord, or equivalent flexible pull element is employed for operating the socket switch to make and break the electrical circuit through the incandescent lamp.

15 A primary object of the invention is to provide a novel and practical construction of all-porcelain pull socket, wherein all exterior metal parts are dispensed with, and a structure is produced possessing special 20 utility as a weather-proof receptacle and specifically meeting the requirements of the Fire Underwriters' Association with respect to sockets of this character.

Another and important object of the 25 invention is to improve the guiding means for the flexible pull element in order to obviate the prevailing objection to the unsatisfactory action of pull chains particularly in an all-porcelain type of pull socket. In that 30 type of pull sockets, great difficulty has so far been experienced in providing an easy movement and action for the pull chain. This action is ordinarily stiff and jerky, and in some directions of pull the pull chain 35 is liable to become caught so as to actually interfere with the operation of the socket switch. Accordingly, one of the distinctive purposes of the present invention is to provide an all-porcelain pull socket having adequate and reliable means for smoothly and 40 evenly guiding the pull chain so that it will freely and readily draw away from the socket in any direction, at the same time causing a positive and responsive actuation 45 of the socket switch. In connection with this phase of the invention, the same contemplates a novel assembly of the interior porcelain parts with relation to the socket switch and its operating mechanism, said 50 assembly being formed with special reference to a proper guiding of the switch lever, and the pull element connected therewith.

With these and other objects in view which will readily appear to those familiar 55 with this class of devices, the invention con-

sists in the novel construction, combination and arrangement of parts hereinafter more fully described, illustrated, and claimed.

The essential and distinctive features of the invention are susceptible of some structural changes without departing from the spirit or scope thereof, but a preferred and practical embodiment of the invention is shown in the accompanying drawings, in which--

60 Figure 1 is a longitudinal sectional view of a porcelain pull socket embodying the present invention, and shown completely assembled, the line of section being indicated by the line 1-1 of Fig. 3.

65 Fig. 2 is a similar view of the completely assembled socket on another line of section, designated by the line 2-2 of Fig. 3.

70 Fig. 3 is a cross sectional view on the line 3-3 of Fig. 1.

75 Fig. 4 is a top plan view of the interior removable insulating cap block, which cooperates with the interior base block to provide an insulated support and housing for the working parts of the socket switch.

80 Fig. 5 is a plan view of the under side of said cap block.

85 Fig. 6 is a perspective view of the porcelain socket body, with a portion of the wall thereof broken away to expose the interior insulating base block and the co-operating elements of the guiding means formed integrally with the porcelain body.

90 Fig. 7 is a perspective view of the removable cap block with all metal parts omitted, and exposing its portion of the guiding means for the switch lever and the flexible pull element connecting therewith.

95 Figs. 8 and 9 are sectional views similar to Figs. 1 and 2 with all metal parts omitted, to more clearly expose the structural features of the porcelain parts and their operative relation.

100 Like reference characters designate corresponding parts throughout the several figures of the drawings.

As already indicated, the distinctive and important features of the present invention reside in the structural characteristics of the porcelain parts and their operative relation 105 with special reference to forming novel and reliable means for smoothly and evenly guiding the pull chain regardless of the direction or angle of pull thereof. Accordingly, referring first to the primary ele- 110

ments of the invention, it will be observed that the socket body 1 is constructed of one piece of porcelain or equivalent insulating material and has no external metal parts associated therewith.

The said one-piece porcelain or equivalent socket body 1 has formed integrally therewith, at an intermediate point between its opposite ends, a solid partition wall 2 which divides the interior of the body into what may be termed for convenience as an upper switch compartment 3 and a lower plug receptacle 4. The upper switch compartment 3 is adapted to be entirely inclosed and covered by a separate detachable porcelain cover member 5 having a flanged edge portion 6 which overlaps and engages the peripheral edge of the body at one end thereof, thus providing an effective sealing cover for the body.

The solid partition wall 2 within the socket body not only separates and isolates one compartment of the body from the other, but also constitutes an interior insulating base block for the socket switch, and to that end, the said wall or base block is recessed at its upper side as at 7 to provide a switch chamber for the socket switch. Furthermore, at one edge of its recessed or chamfered side, the said wall or base block is formed with a segmental rabbet 8 constituting a guiding ledge for the swinging end of the switch lever to be presently referred to, and the rabbeted formation which provides this ledge also produces stop shoulders 9 and 10 at the opposite ends thereof for limiting the forward and backward movements of the switch lever. In connection with the segmental ledge formation 8, it will be observed particularly by reference to Figs. 6 and 8 of the drawings that what may be termed the outer end portion of the guiding ledge of the rabbet 8 directly adjoins a guide projection 11 at one edge of which is formed the shoulder 10, and whose outer surface 12 is evenly and smoothly curved on the arc of a circle which merges directly into the inner convexly curved guide wall 13 of an outwardly projecting guide tube or horn 4.

The inner guiding wall 13 of the guide tube or horn 14 is formed on the arc of a circle, so that said wall not only merges, on curved lines, into the curved guide surface 12 of the projection 11, but also merges on a curved line into the inner wall of the body over the guiding ledge 8, thereby providing a continuously curving guide surface at all points for the pull chain or equivalent flexible pull element. Furthermore, the guide tube or horn 14 is formed as an integral part of the porcelain body 1 and has a flared or bell mouth 15 so that the extreme outer edges of the tube are rounded or curved, thereby permitting the pull element to be

smoothly and evenly drawn in any or all directions without the objectionable jerk which is common to the action of many commercial forms of pull sockets. Also, in order to obtain the action desired, the guide tube 14 is preferably radial to the axis of the body and not tangentially disposed.

In order to properly provide for the mounting and housing of the switch parts, there is associated with the base block 2 an interior removable insulating cap block 16, also made of porcelain or equivalent insulating material. This cap block fits within the switch compartment 3, and through the medium of the connecting screws is held in proper position upon the guide projection 11, and a corresponding rest projection 17 formed at an opposite point within the socket body. The structural feature of importance in the cap block 16 is the formation in one edge thereof of a segmental guiding recess or groove 18 which is co-extensive with and overlies the segmental guiding ledge 8 to complete the guiding means for the swinging end of the switch lever and the pull element connecting therewith.

Any suitable pull switch mechanism may be combined with the porcelain parts described, but it is preferred to employ a pull switch of the general character of that disclosed in my former Patent No. 995,241, dated June 13, 1911. This kind of switch is shown in the drawings, and referring generally to the essential elements thereof, the same includes a pair of spring contact plates 19 and 20, one of said plates 20 being connected by 21 with the center plug contact 22 located in the receptacle part of the body, and the other spring contact plate 19 being connected through a line of connections 23, 24, 25 and 26 with one of the binding terminals 27. The other binding terminal 28 is connected by a line of connections 29, 30 and 31 with the screw shell contact 32 within the receptacle part of the socket. Suitable connecting screws hold the various parts together in the assembled relation shown.

In addition to the contact springs 19 and 20, the pull socket switch includes a rotatable cam element 33 and a ratchet operating mechanism having the swinging switch lever 34 to which is connected the inner end of the pull chain or equivalent flexible pull element 35. The relation of the switch lever 120 and the pull chain element to the various porcelain guiding elements herein referred to is plainly shown in Fig. 3 of the drawings, and it will be observed therefrom that an easy and smooth guiding movement is insured for both the switch lever and the pull element so that a positive and reliable actuation of the switch is obtained without the jerkiness and "catching" incident to the operation of many forms of pull switches. 130

From the foregoing, it is thought that the construction, action, and many advantages of the herein-described improvement will be readily apparent without further description, and it will be understood that changes in the form, proportion, and minor details of construction may be resorted to without departing from the spirit or sacrificing any of the advantages of the invention.

10 I claim:

1. An all-porcelain pull socket including a porcelain body provided with an interior integral base block and formed with an interior segmental guiding ledge and an integral outward projecting guide tube having an inner wall curving into the body over said ledge, a removable porcelain cap block seated upon the base block and having a
- 15

segmental recess over said ledge, and a socket switch.

2. An all-porcelain pull socket including a porcelain body provided with an interior integral base block, and an interior segmental guiding ledge and an integral outward projecting guide tube, a removable porcelain cap block seated upon the base block, a socket switch housed between the two blocks, and a porcelain cover member arranged over one end of the body.

In testimony whereof I hereunto affix my **30** signature in the presence of two witnesses.

EDGAR H. FREEMAN.
